UNITED STATES PATENT OFFICE

PERCY FRANK GUNNING, OF LIVERPOOL, ENGLAND, ASSIGNOR TO ASSOCIATED TELEPHONE & TELEGRAPH COMPANY, OF CHICAGO, ILLINOIS, A CORPORATION OF DELAWARE

TELEPHONE SYSTEM

Application filed March 25, 1929, Serial No. 349,804, and in Great Britain May 23, 1928.

The present invention relates to improvements in telephones systems and more particularly concerns semi-automatic telephone systems in which an operator is enabled by 5 means of a key set, to control the operation of automatic switches to establish connections with the subscribers' lines, though it will be understood that the scope of its application need not necessarily be limited to 10 the arrangement shown.

In known circuit arrangements of this type, the operation of the digit keys by the operator, in accordance with wanted subscribers' numbers, effects the operation of 15 certain relays, known as storing relays. The usual arrangement is that, for each digit, particular relays or combinations of relays in a group are energized, in accordance with the key operated and the contacts of these 20 relays are connected in such a manner that they control the subsequent sending of the digits. As a result of this, each group of storing relays has to be provided with a comparatively large number of springs, and as 25 most numbering schemes require the sending of at least four digits, the total number of contact springs on the relays becomes unduly large.

The object of the present invention there- 30 fore is to provide a simplified circuit which will enable the number of spring combinations to be considerably reduced, and according to one feature of the invention this is accomplished by arranging that only the 35 first storing group of relays carry the necessary spring combinations and connections, to control the sending of the subscriber's number in accordance with the relay or relays operated. Relays in the other storing 40 relay groups only carry sufficient springs to control the relays in the first group, and the relays in the first group release after the sending of each digit, to be thereafter re-operated in accordance with the setting of 45 the relays in each of the subsequent groups.

The invention will be better understood from the detailed description of one method of carrying it into effect which follows, reference being had to the accompanying draw- 50 ings, which show, by way of example, the in-

vention adapted for use on a four digit storing and sending scheme from an operator's key-sending position. In order to facilitate the understanding of the invention, Fig. 2 should be placed to the right of Fig. 1, with 55 the corresponding lines in alignment.

In Fig. 1, DK represents the operator's digit key strip, relays W, X, Y and Z the first group of storing relays carrying the necessary contact combinations and connec- 60 tions so that potential may be applied to any of the terminals 1 to 0 in accordance with the relays operated, to control the sending of the necessary digits; and ICS represents the input control switch which extends the operating leads from the digit keys to each of the storing groups in turn. It will be clearly understood that if desired, the input control switch may be of the relay switching type, in place of the rotary switch type 65 shown. In Fig. 2, the second, third, and fourth storing relay groups are shown comprising relays W¹, X¹, Y¹, Z¹, W², X², Y², Z²; and W³, X³, Y³, Z³, respectively. Also, a portion of the sending control switch is 70 shown at SCS.

As soon as the equipment is in readiness to receive the call the operator operates the digit keys in accordance with the desired subscriber's number and it will be assumed, by 80 way of example, that this number is 3456. The operation of digit key 3 extends earth over wiper 12 and first bank contact of the input control switch ICS, upper winding of relay Y, winding of relay DS to battery. 85 Relays Y and DS operate in series in this circuit, relay Y locking itself from battery, over its lower winding, armature 14 and front contact, conductor 15, first bank contact and wiper 31 of the sender control switch SCS, to earth, and relay DS energizing and completing the circuit of the magnet DM of the input control switch ICS at armature 16. When the key 3 is released, relay DS re- 90 stores and allows the magnet DM to de-energize and move the wipers on to the next bank contacts. The operation of the next digit key i. e. 4, extends earth over wiper 18 and second bank contact of the input control switch, conductor 17, upper winding of relay 95 100

Z¹, conductor 18, winding of relay DS to battery. Relay Z¹ operates in this circuit and locks itself at armature 19 to earth on a convenient holding conductor say for instance, conductor 46; relay DS energizes in series with relay Z¹, and operates the magnet DM as before. The release of the key permits the magnet to restore and move the wipers forward one more step and when the next digit key 5 is operated, earth is extended over wipers 10 and 11, and their third bank contacts, conductors 20 and 21, upper windings of relays W2 and X2, respectively, conductor 18, winding of relay DS to battery. Relays 10 W2 and X2 energize in the two branches of this parallel circuit and lock energized over their lower windings at armatures 22 and 23, respectively, to earth on conductor 46, and relay DS, as before, effects the operation of 15 the stepping magnet of the input control switch. Similarly, when the digit key 6 is operated, relays W3 and Y3 operate over wipers 10 and 12 and the fourth bank contacts and conductors 24 and 25 respectively, 20 in parallel. These relays will operate and lock energized as before, and relay DS will again cause the magnet DM to operate to cause input control switch to step forward one step.

25 The operation of relay Y in the first storing relay group, Fig. 1, connects earth over conductor 26 to terminal 3, from armature 27 and back contact, armature 28, and back contact, armature 29 and front contact, armature 30 and back contact, conductor 26 to terminal 3, and this terminal will be connected to a part of the sending circuit so that sending will be stopped when three impulses have been sent. When the first digit, that is, the 30 three impulses have been sent, the sender control switch is stepped once, by well known circuit methods not shown in the drawings, and the locking circuit for the relays in the first storing group is opened. The relays in 35 the first storing group which are operated therefore release, but as soon as the wipers of the sender control switch rest on their second bank contacts a circuit is again completed to operate relays in the first group, as 40 is determined by the operated relays in the second group. As relay Z¹ is operated in the second group, a circuit may be traced for relay Z of the first group, from earth, wiper 31 and second bank contact of the sender control switch SCS, conductor 32, armature 33 and front contact, conductor 34, lower winding of relay Z in the first storing group to battery. Relay Z operates and connects earth over conductor 35 to terminal 4 from 45 armature 27 and back contact, armatures 28 and 29 and their respective back contacts, armature 36 and front contact, conductor 35 to terminal 4, which terminal is connected to the sending circuit so that sending is stopped 50 when four impulses have been sent.

When this series of impulses has been sent, the sender control switch SCS again steps one step, relay Z in the first relay group restores, and circuits are now completed to operate relays W and X from earth on wipers 51 and 52 and their third bank contacts, armatures 37 and 38 and front contacts of relays W2 and X2 of the third group respectively, conductors 39 and 40 respectively, lower windings of relays W and X to battery. Earth is 55 now connected over conductor 41 to terminal 5, from armature 27 and front contact, armature 42 and front contact, conductor 41 to terminal 5, so that the next series of impulses sent out will be 5. Similarly, after this series, 60 the switch SCS again steps one step, relays W and X restore, and circuits are closed over wipers 51 and 53 for the re-operation of relay W and the operation of relay Y over armatures 43 and 44 respectively of relays 65 W3 and Y3, of the fourth group. Earth is therefore now extended over conductor 45, to terminal 6, so that the next series of impulses which is sent out is 6.

After completion of sending the relays in the second, third and fourth storing relay groups will be restored to normal by the opening of the common holding circuit, which it will be understood may be controlled by other suitable circuit features.

From the foregoing description and the drawings it will be appreciated that according to the present invention the large spring combinations necessary to control the digit to be sent need only be equipped on the relays in the first storing relay group, the remaining storing groups having only sufficient springs as is necessary to control the operation of the first group relays.

What I claim as new and desire to secure by Letters Patent is:—

1. In an arrangement for controlling the operation of an impulse sender, a plurality of relay groups, means for operating said relay groups in turn to record successive digits of a number, and means whereby one of said relay groups controls the operation of the sender to transmit all the digits recorded.

2. In a register sender, a plurality of registers, means for setting said registers to record successive digits in a number, means for restoring the first register after the digit recorded thereon has been transmitted, and means for automatically resetting said first register under control of the second register.

3. In a register sender, a plurality of registers, sufficient contacts on the first register for controlling the operation of an impulse sender, and contacts on the remaining registers for controlling the resetting of said first register.

4. In a register sender, a plurality of registers each comprising a plurality of relays, means for setting the relays of said registers to record successive digits of a number, a

plurality of contacts on the first register for causing an impulse sender to transmit impulses corresponding to the digit recorded on said register, and means for resetting said first register in accordance with the digits recorded respectively on the remaining registers.

5. In an arrangement for controlling the operation of an impulse sender, a plurality of relay groups, means for operating relays in said relay groups in turn to record successive digits of a number, means whereby one of said relay groups controls the operation of the sender to transmit all the digits recorded, and means for restoring said last mentioned relay group and for resetting the same between the transmission of successive digits.

In testimony whereof I have signed my name at London, England, this 28th day of February, 1929.

PERCY FRANK GUNNING.
